DESIGN FOR A COMBINED KITCHEN SHELF AND BRACKETS THEREFOR, OR SIMILAR ARTICLE

Albert M. Feldman, New York, N. Y.

Application June 14, 1938, Serial No. 77,824

Term of patent 14 years

To all whom it may concern:

Be it known that I, Albert M. Feldman, a citizen of the United States, residing at 309 West 54th Street, New York city, in the county of New York and State of New York, have invented a new, original, and ornamental Design for a Combined Kitchen Shelf and Brackets Therefor, or Similar Article, of which the following is a specification, reference being had to the accompanying drawing, forming a part thereof.

The figure is a front perspective view of the article, showing my new design, the end incompletely shown being identical with the end completely shown.

I claim:

The ornamental design for a combined kitchen shelf and brackets therefor, or similar article, as shown and described.

ALBERT M. FELDMAN.
